EDGE GRINDING MACHINE FOR LENSES

Filed April 10, 1919 3 Sheets-Sheet 3

UNITED STATES PATENT OFFICE.

ELI M. LONG, OF GENEVA, NEW YORK, ASSIGNOR TO THE STANDARD OPTICAL COMPANY, OF GENEVA, NEW YORK, A CORPORATION OF NEW YORK.

EDGE-GRINDING MACHINE FOR LENSES.

Application filed April 10, 1919. Serial No. 288,897.

To all whom it may concern:

Be it known that I, ELI M. LONG, a citizen of the United States of America, and resident of Geneva, N. Y., in the county of Ontario, in the State of New York, have invented new and useful Improvements in Edge-Grinding Machines for Lenses, of which the following, taken in connection with the accompanying drawings, is a full, clear, and exact description.

This invention relates to certain improvements in edge grinding machines for lenses, the main object of which is to automatically and uniformly bevel the edge of the lens from one or both sides by rotating said lens edgewise against a special form of rotary grinder preparatory to receiving the usual rims.

In many forms of concavo-convex such as toric and cylindrical lenses whether elliptical or circular, different points in the perimeter or periphery are disposed in different planes relatively to that of the center of the lens, and one of the specific objects of my present invention is to cause all of such points to contact with the grinder in the same plane and with substantially the same pressure and to utilize the grinding surfaces of the grinder in combination with the free axial and radial movements of the lens holder as a means for carrying out this object.

Another, not less important, object, is to divide the grinder into two similar circular sections or grinding elements opposed to each other axially and to provide their adjacent ends with beveled circumferentially extending edges meeting at the point of contact with the lens to form a V-shaped groove for beveling both edges of the lens simultaneously.

A further object is to arrange these grinding elements in such manner as to permit the use of suitable truing tools for maintaining the desired bevels on the adjacent ends of said elements during the process of grinding of the lens so that the bevels on the edge of the lens may be made correspondingly uniform.

Other objects and uses relating to specific parts of the machine will be brought out in the following description.

In the drawings:

Figure 1 is a top plan of an edge grinding

machine for carrying out the objects of my invention in which the axes of the grinding elements are parallel but offset radially at substantially right angles to a radial line passing through the point of contact between the lens and grinding elements.

Figure 2 is a side elevation of the main portion of the machine shown in Figure 1 except that the pivotal connections between the floating support for the lens holder and bracket upon which it is mounted, together with the driving shaft are shown in section.

Figure 3 is an enlarged detail vertical sectional view through the pattern rest and adjacent portion of the supporting frame for the lens holder.

Figure 4 is an enlarged vertical sectional view of the main portion of the machine taken on line 4—4 Figure 1.

Figure 5 is a transverse vertical sectional view of a slightly modified form of machine in which the grinding elements and their axes are disposed at an angle to each other so that the beveled edges meet at the point of contact with the lens.

The construction shown in Figures 1 to 4 inclusive, comprises a main supporting frame —1—, grinder composed of opposite circular grinding elements —2—, a rotary lens holder —3— for supporting a lens —a—, and a floating support —4— for the lens holder together with suitable driving means for the grinding elements and additional driving means for the rotary lens holder hereinafter described.

The frame —1— may be of any desired construction provided with a reservoir or trough —5— adapted to receive the drip of the water which is preferably introduced between the grinding elements through one or both of the hollow supporting shafts —6— therefor.

The grinding elements —2— are mounted in axially opposed relation or end to end upon separate hollow rotary shafts —6— and —6— which are journaled in parallel but offset relation in suitable bearings —7— on the main frame —1— at the outer ends of the grinders, each shaft being provided at its inner end with a circumferentially grooved collar —8— for receiving the inner edge of the corresponding grinding element —2— which is rigidly clamped to the collar —8— by a supplemental collar

—9— screwing upon the hub of the first named collar as shown more clearly in Figure 4.

The peripheries of the adjacent ends of 8 the grinding elements —2— are provided with circumferentially extending beveled edges —10— and —10— converging inwardly toward the meeting faces to form a V-shaped groove at the point of contact 16 with the edge of the lens —a— so as to bevel the edge of the lens from both sides simultaneously during the grinding operation.

The axes of the grinding elements are 15 preferably disposed in a substantially horizontal plane but are offset horizontally to cause a similar offset relation of the peripheries of the grinding elements —2— a distance slightly greater than the depth of 20 the beveled edges —10— whereby the beveled edge at the front of one grinding element will project forwardly beyond the corresponding edge of the other grinding element, and the rear edge of the last named 25 element will project horizontally beyond the corresponding edge of the first named element to permit the use of diametrically opposite truing tools as —11— for keeping the beveled edges —10— at the desired angle 30 and circularity.

In other words, the grinding elements are offset at substantially right angles to the vertical plane of the axis of the lens holder —3—, the axis of which is parallel with 35 those of the grinding elements —2— and is adapted to hold the lens —a— edgewise in contact with both the beveled edges —10—, at the point where said beveled edges register to form the transverse V-shaped groove 40 previously mentioned, or in a vertical plane substantially midway between the axes of the grinding elements.

The rotary lens holder may be of any 45 well known construction, but in this instance, consists of a pair of opposed heads —12— and —13— between which the lens —a— is clamped, the head —12— together with a former —40— being mounted upon a rotary shaft or spindle —14— which in 50 turn are driven by intermeshing gears —15—, or may be rotated by a hand wheel —16— on the outer end of the shaft or spindle —14— as shown more clearly in Figure 4.

55 The head —12— and former —40— may be locked to the shaft in any suitable manner which will permit both of those parts to be removed when necessary, it being understood that the particular form of lens holder 60 forms no part of this invention except broadly in combination with the grinding elements.

The head —13— is mounted upon a separate spindle —17— which together with the 65 spindle —14— are journaled in suitable

bearings —18— and form a part of a floating support —4— for the lens holder.

The spindle —17— and its head —13— are movable axially against the action of a retracting spring —19— which serves to yieldingly hold the head —13— in clamping position upon the lens —a—, but is adapted to be released against the action of said spring by means of a hand lever —20— shown in 75 Figure 1.

The floating support for the lens holder is shown as composed of two sections —21— and —22—, the section —21— being pivotally mounted at —23— upon an upright bracket —24— of the main supporting frame to swing horizontally or about a vertical axis, while the section —22— is hinged at —25— to the front end of the section —21— to swing vertically or about a horizontal axis and constitutes the direct support for the rotary lens holder. 80

It, therefore, follows that the lens holder has two distinctive movements, one of which is axial to enable all portions of the edge of the lens which may be in different planes 85 to automatically register with or follow in the V-shaped groove formed by the beveled edges —10—, the vertical movement of the section —22— serving to compensate for varying radii of the lens at its point of contact with the grinder.

A driving shaft —26— is journaled in a horizontal position upon the rear end of the frame —1— or rather upon the upright bracket —24— and is provided with tight 100 and loose pulleys —27— and —28— adapted to be connected by a belt (not shown) to any available source of power.

This driving shaft is also provided with a 105 pair of pulleys —29— connected by belts —30— to somewhat larger pulleys —31— on the shafts —6— and —6— of the grinding elements —2— and —2— as shown more clearly in Figure 1.

Secured to the same driving shaft is a 110 beveled gear —32— which meshes with a similar gear —33— on the shaft —34—.

The shaft —34— is provided with a gear —35— meshing with a similar gear —36— which in turn transmits motion to the gear —15— through the medium of an idler —37— thus completing the means for transmitting rotary motion from the driving shaft —26— to the lens holder —3—. 115

It is evident, however, that any other means may be employed for driving the grinding elements —2— and the lens holder —3—, and, therefore, I do not limit myself to the construction shown and described. 120

The bearings —7— for the shafts —6— of the grinding elements are preferably adjusted axially to permit the meeting faces of the grinding elements to be brought into close contact, and for this purpose is pro- 125

vided adjusting screws —38—, one for each bearing which also serve to register the V-shaped groove in the grinder with the lens, the bearings being held in their adjusted position by clamping bolts —39— as shown in Figure 4.

Both of the grinding elements —2— are preferably rotated at the same speed and in the same direction, while the lens holder —3— is rotated at suitable speed in an opposite direction to accelerate the grinding effect upon the lens.

The size and shape of the lens is determined by the usual former or pattern —40— riding against an adjustable rest —41— which may be adjusted toward and from the axis of the lens holder by means of a screw —42—, the rest —41— being pivoted at —43— to the section —21— of the floating support for the lens holder as shown more clearly in Figure 3.

In Figure 5 is shown a pair of opposed grinding elements —2'— having their axes disposed at an angle to each other but in substantially the same vertical plane so that the upper edges of their adjacent faces meet in substantially the same plane to form thereat a V-shaped groove with which the edge of the lens is adapted to register for beveling the edges thereof.

The shafts as —6— upon which the grinding elements —2'— are clamped are also disposed at an angle to each other, but in the same vertical plane and are journaled in bearings —7'—, the latter being also adjustable axially and clamped in their adjusted position by devices similar to those previously described.

It is evident from the foregoing description that the adjacent faces or ends of the grinding elements —2'— in horizontal plane passing through their axes will be spaced some distance apart sufficient to permit the use of truing devices similar to those previously described in keeping the beveled edges —10— at the desired angle.

The water for moistening purposes is preferably introduced between the grinding elements —8— through one or both of the hollow shafts —6— and for this purpose I have shown a water supply pipe —w— leading from any suitable source of supply into the outer end of the right hand shaft —6— Figure 4, the passage through the shaft being shown by dotted lines.

What I claim is:

1. In a lens edge beveling machine, a rotary grinder having opposed beveled faces, a rotary lens holder and driving means therefor, and means for supporting the lens holder with the edge of the lens in simultaneous contact with both of the beveled faces, said supporting means being moved lengthwise of the axis of the grinder independently of said driving means by con-
2. In a machine for beveling the edge of a lens, a rotary grinder having opposed beveled faces, and means for rotatably supporting a lens edgewise against both of said faces simultaneously and allowing it to move in opposite directions lengthwise of its axis of rotation solely by contact of the edge of the lens with said faces in case different portions of the edge of the lens rotate in different planes.
3. In a lens edge beveling machine, a rotary grinder having opposed beveled faces, and means for rotatably supporting a lens edgewise against both of said faces simultaneously including supporting members movable about axes at right angles to each other and actuated by the axes by contact of the lens with said beveled faces.
4. In a lens edge beveling machine, a rotary grinder having juxtaposed beveled faces, means for rotatably supporting a lens edgewise against both of said faces simultaneously, said means having unrestrained movement in opposite directions lengthwise of the axis of the grinder whereby the contact between the edge of the lens and beveled faces constitute the only means for moving the lens lengthwise of said axis in case different portions of the edge of the lens rotate in different planes.
5. In a lens edge beveling machine, a grinder rotatable about a horizontal axis and provided with juxtaposed beveled faces, a rotary lens holder above the grinder for supporting the lens edgewise against both of said faces simultaneously, and a sectional support for the lens holder having one of its sections pivoted to swing about a vertical axis and another section pivoted to the first named section to swing about a horizontal axis.
6. In a machine for beveling the edges of lenses, a grinder rotatable about a horizontal axis and provided with juxtaposed peripheral beveled faces, means for rotatably supporting a lens edgewise against both of said beveled faces simultaneously directly over the axis of the grinder, said means including a member hinged to swing about a vertical axis, and an additional member hinged to the first named member to swing about a horizontal axis some distance from the axis of rotation of the lens holder, the movement of the supporting means for the lens holder in opposite directions about the vertical axis being unrestrained and the contact of the lens with the beveled grinding faces constituting the sole means for causing axial movement of the lens holder in case different portions of the edge of the lens rotate in different planes.
7. In an edge grinding machine of the

- character described, a rotary grinder having opposed circumferentially extending beveled edges, floating means for rotatively holding a lens edgewise against both of said beveled edges at the same time, whereby portions of the edge of the lens rotating in different planes co-operating with the bevel edges of the grinder will automatically shift said lens holding means both axially and radially.
8. In an edge grinding machine of the character described, a rotary grinding element having opposed beveled edges, a rotary lens holding element for supporting a lens edgewise against both of said beveled edges at the same time, the engagement of the lens with the bevel edges causing one element to automatically shift axially to compensate for variations in the planes of rotation of different points in the edge of said lens.
9. In a machine for grinding the edges of lenses, the combination of a rotary grinding element having opposed beveled edges, a supporting frame for said grinding element, a bracket rising from the frame at the rear of the grinding element, a rotary lens holder above the grinding element directly over the axis thereof for supporting a lens edgewise in contact with both of said beveled edges, a support for the rotary lens holder composed of sections, one section being pivoted to the bracket to swing about a vertical axis, and the other section being pivoted to the first named section to swing about a horizontal axis, a driving shaft journaled on the bracket, means for transmitting motion from the driving shaft to the grinding ele-
- ment, and separate means for transmitting motion from the driving shaft to the rotary lens holder.
10. In a machine for grinding the edges of lenses, a rotary grinder composed of separate disks and separate supporting shafts therefor offset radially one from the other in one direction and inclined in another direction at right angles to a plane of offset, said disks having adjacent ends facing each other and provided with peripheral beveled faces, and means for rotatably supporting a lens edgewise in contact with both of said beveled faces at their point of nearest approach to each other.
11. In an edge grinding machine for lenses, a rotary grinder having opposed grinding faces, and a rotary, axially movable lens holder supporting the lens edge-wise against both of said faces, and actuated axially thereby.
12. In an edge grinding machine for lenses, the combination of a rotary grinder having opposed peripheral grinding faces, and a rotary lens holder supporting the lens edgewise against both of said faces, said lens holder being movable axially and radially relative to the grinder, and both movements controlled by contact of the lens with said grinding faces.

In witness whereof I have hereunto set my hand this 2nd day of April, 1919.

ELI M. LONG.
